Application February 15, 1952, Serial No. 271,701

AMPOULE BREAKER

Severo Reyes, Laredo, Tex.

3 Claims. (Cl. 81—3)

This invention relates to tube or ampule breakers and more particularly to a device for breaking the sealed glass tubes or ampules in which sterile surgical sutures are stored.

It is among the objects of the invention to provide an improved suture tube or ampule breaker which will receive ampules of various sizes and effectively break the ampules at the score lines provided thereon; which can be maintained in a sterile condition and protects the contents of the ampule from contact with the hands of a person breaking the ampule, as well as protecting the hands of such person from injury by broken or splintered glass of the ampule; which is of small size and can be easily held in the hands for use; and which is simple and durable in construction, economical to manufacture, easy to use, and positive and effective in use.

Other objects and advantages will become apparent from a consideration of the following description and the appended claims in conjunction with the accompanying drawing wherein:

Figure 1 is a side elevational view of an ampule breaker illustrative of the invention;

Figure 2 is a longitudinal cross sectional view on the line 2—2 of Figure 1; and

Figure 3 is a somewhat diagrammatic view illustrating the manner in which the device is used to break ampules.

With continued reference to the drawing, the ampule breaking device comprises tubular bodies 10 and 11 of elongated cylindrical shape and of a diameter to loosely receive a surgical suture ampule, as indicated at 12, therein.

The body 10 is open at one end and is closed at its other end by a closure plug 13 screw threaded or otherwise secured in the corresponding end of the tubular body, and is provided with diametrically opposed slots 14 and 15 extending longitudinally thereof from a location spaced from the open end to the closed end of the body.

A piston 16 is slidably mounted in the body 10 and a coiled compression spring 17 is disposed in the body between the piston 16 and the closure plug 13 and resiliently urges the piston toward the open end of the body. A pin 18 extends through the piston 16 and through the slots 14 and 15 projecting outwardly from the body at opposite sides of the latter and substantially perpendicular to the longitudinal center line thereof. Sleeves 19 and 20 are disposed on the pin 18, one at each opposite side of the body 10, and provide arms projecting outwardly from the body for engagement by the fingers of a person using the device to move the piston 16 against the

resilient spring 17 and the piston 16 until the piston 16 is urged into the body 10 and the pin 18 is urged into the slots 14 and 15.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

When the piston 16 is urged into the body 10, the pin 18 is urged into the slots 14 and 15 and the piston 16 is urged into the body 10.

is broken. The parts of the ampule and the ampule contents are then discharged from the bodies 10 and 11 onto a sterilized surgical tray from which the content of the ampule, such as a surgical suture, may be removed for use by the surgeon.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. An ampule breaker comprising a first tubular body having one end open and angularly spaced apart slots extending longitudinally thereof from a location spaced from said one end to the other end thereof, a plug closing said other end, a piston slidable in said first tubular body, arms projecting outwardly from said piston one through each of said slots and providing finger engageable means for moving said piston toward said other end of the body to position an ampule at a position of adjustment projecting from said one end of said body, a compression spring in said body between said plug and said piston resiliently urging said piston toward the open end of said body, and a second tubular body having at least one open end for receiving the portion of an ampule projecting from said first body and breaking the ampule upon angular movement of said bodies relative to each other.

2. An ampule breaker comprising a first tubular body, manually adjustable means slidably mounted in said first body for adjustably posi-

tioning an ampule in the latter with a portion of the ampule projecting from one end of the body, and a second tubular body adapted to receive at one end the portion of an ampule projecting from said first body, said bodies being both of a sufficient length to be comfortably grasped one in each hand of a person using the breaker and being effective to break the ampule upon angular movement of the bodies relative to each other when opposite end portions of the ampule are respectively disposed in adjacent end portions of said tubular bodies.

3. An ampule breaker comprising a first tubular body, manually adjustable means slidably mounted in said first body for adjustably positioning an ampule in the latter with a portion of the ampule projecting from one end of the body, a second tubular body of substantially the same diameter as said first body adapted to receive at one end the portion of an ampule projecting from said first body, said bodies being both of a sufficient length to be comfortably grasped one in each hand of a person using the breaker and being effective to break the ampule upon angular movement of the bodies relative to each other when opposite end portions of the ampule are respectively disposed in adjacent end portions of said tubular bodies, and an elongated flexible element connected at its respectively opposite ends to said bodies to hold said bodies together.
